CLAIM

The ornamental design of a sign panel for a vending machine, as shown and described.

DESCRIPTION

FIG. 1 is a right front perspective view of the sign panel for a vending machine showing our new design;

FIG. 2 is a front elevational view of the sign panel for a vending machine of FIG. 1;

FIG. 3 is a right side elevational view of the sign panel for a vending machine of FIG. 1;

FIG. 4 is a left side elevational view of the sign panel for a vending machine of FIG. 1;

FIG. 5 is a rear elevational view of the sign panel for a vending machine of FIG. 1;

FIG. 6 is a top plan view of the sign panel for a vending machine of FIG. 1; and,

FIG. 7 is a bottom plan view of the sign panel for a vending machine of FIG. 1.

The broken line showings are for environmental purposes only and form no part of the claimed design.
